UNITED STATES PATENT OFFICE.

CHARLES EDWARD SHELBY BURCH AND ARTHUR LEWIS KASSON, OF
SEATTLE, WASHINGTON.

GAS-PRODUCER.

SPECIFICATION forming part of Letters Patent No. 619,538, dated February 14, 1899.

Application filed October 5, 1897. Serial No. 654,141. (No model.)

To all whom it may concern:

Be it known that we, CHARLES EDWARD SHELBY BURCH and ARTHUR LEWIS KASSON, citizens of the United States, residing at Seattle, in the county of King and State of Washington, have invented a new and useful Apparatus for Placer-Mining, of which the following is a specification.

Our invention relates to a gas-producer for an apparatus for placer-mining especially designed for service in the cold regions of the north, where the ground is frozen for a major portion of the year and where it is consequently difficult to mine the earth; and the primary object that we have in view is to provide a simple and efficient apparatus for generating heat, which may be used as the agent for thawing the frozen ground to enable the same to be mined with picks or bars to good advantage during cold weather.

A further object of the invention is to provide an improved generator by which a superheated combustible gas may be produced and supplied in large volumes from a central station to the miner or miners, such gas being produced very economically and rapidly from cheap fuel.

With these ends in view our invention consists in a generator consisting of retorts for the conversion of wood into gas and with superheaters operatively connected with the retorts and arranged in such relation to the furnace and the retorts as to be exposed to the direct action of the heat for the purpose of highly heating the gas produced by the action of the heat in the retorts on the substance therein; and the invention further consists in the novel construction, combination, and arrangement of parts, as will be hereinafter fully described and claimed.

To enable others to understand our invention, we have illustrated the preferred embodiment thereof in the accompanying drawings, forming a part of this specification, and in which—

Figure 1 is a perspective view illustrating in a general way the mode of service of our generator for a plant for placer-mining. Fig. 2 is a vertical transverse sectional elevation through the generator on the plane indicated

by the dotted line 2 2 of Fig. 3. Fig. 3 is a sectional plan view on the plane indicated by the dotted line 3 3 of Fig. 2. Fig. 4 is a diagrammatic view illustrating one means for thawing and ventilating a mine.

55

Like numerals of reference denote corresponding and like parts in each of the several figures of the drawings.

In a plant for placer-mining in the cold gold-bearing regions of the north we employ a gas-generator indicated in its entirety by the numeral 1 in the drawings, and in connection with said generator we provide an off-bearing line of asbestos-protected hose 2, which leads the highly-heated gas to a discharge-nozzle 3, 60 which may be directed by the miner against the frozen earth or soil in the mine for the purpose of thawing the earth to such an extent as to be mined by picks or bars to good advantage.

70

We have thus far indicated in a general way the nature of the apparatus with which our gas-generator is used, and we will now proceed to a detailed description of the gas-generator shown by Figs. 1 to 3, inclusive, of the drawings. This gas-generator is designed to produce gas from wood, as this substance is very cheap and found in abundance at the sections of the country where mining is carried on. The generator embodies a furnace 80 5, having the grates 6 and the division-wall 7, and on the masonry or brickwork of the furnace are erected the horizontal metallic retorts 8 9, which are arranged in horizontal positions over the combustion-chamber of the 85 furnace and in parallel relation to each other. These retorts 8 9 are entirely independent one from the other, and each is constructed with a closed head at the rear end, while the front ends of said retorts are equipped with hinged doors, through which the fuel may be charged.

Rising from the retorts, preferably at the middle thereof, are the outlet-pipes 10 10', which are joined by the horizontal connecting-pipe 12 through the medium of the unions or couplings 11, and said unions or the horizontal pipe 12 have the vent-valves 13, through which the smoke and vapors may be discharged at the beginning of the operation of carbonizing the wood in the retorts. To this 95 100

horizontal pipe 12 is connected an off-bearing gas-pipe 15, preferably by means of a union 14, which is attached centrally to the pipe 12, and stop cocks or valves 16 are provided in this pipe 12 on opposite sides of the union 14 for the off-bearing pipe 15 in order to cut off communication of each retort with the off-bearing pipe whenever it is desired to charge either of the retorts with fuel.

10 Within the walls of the generator-furnace are arranged the manifolds 17 18, forming the superheater, which lies between the grate-bars of the furnace and the retorts in order to expose the wood-gas contained in said superheater to the intense heat generated in the furnace chamber or chambers. The manifold 17 is situated below the retort 8, while the other manifold 18 is situated below the retort 9, and these manifolds are isolated one from 15 the other by the intervening bridge or division wall 7. Each manifold consists of a series of straight pipes or tubes connected in pairs by the return-headers 19, and said headers are provided with removable plugs attached thereto in line with the passage through the pipes or tubes, so that the plugs may be removed to enable easy access to be obtained to the pipes or flues for the purpose of cleaning the same with a brush or scraper 20 of any sedimentary deposit that may accumulate in the pipes of the manifolds. The headers of the superheater-manifolds extend beyond the furnace-walls, so that they are exposed and ready access may be had to the 25 removable plugs thereof.

30 The off-bearing pipe 15 from the connecting-pipe of the independent retorts leads to and is connected with one end of the manifold 17, and the other end of this manifold 17 is coupled by a return-bend 20 to one end of the other manifold 18, said return-bend extending around the bridge or division wall of the furnace, as shown by Fig. 3. The described arrangement and connection of the 35 manifolds and the off-bearing gas-pipe enables the gas from either or both of the retorts to first circulate through one manifold and then through the other manifold of the heater, thus exposing the gas to the direct action of the 40 intense heat in the generator-furnace and causing it to traverse a large area of intensely-heated pipes or flues, whereby the gas is superheated before it is conducted to the discharge-nozzle to be used as the agent for thawing frozen ground preparatory to mining the 45 same.

As before indicated, our improved generator is designed for use in an apparatus for placer-mining, and in this adaptation of the 50 generator a line of hose 2 is coupled at one end to the manifold 18 of the superheater, and the other end of this line of hose is attached to the heel of the discharge-nozzle 3. Of course the line of hose may be of any desired length suitable to lead from the generator erected on the surface down into the mine where the miners are stationed, and in

order to enable the hose which conducts the highly-heated gas to be handled by the operator we provide a hose which is protected by 70 asbestos or other heat-resisting medium.

In the practical service of the apparatus the fires in the furnace are kindled and the wood is charged in one or both retorts, the valve or valves 13 being opened at first to 75 permit the smoke to escape, after which the vent-valves are closed. The gas evolved by the carbonization of the wood in the retort or retorts is conducted by the pipes to the manifold 17, through which the gas flows to the other 80 manifold 18, and thence to the line of hose 2, by which the gas is conducted to the nozzle 3. The gas is highly heated in its passage through the pipes or flues of the manifolds, because the latter are exposed to the direct action of 85 the heat in the furnace; but the retorts are exposed sufficiently to the furnace heat to properly carbonize the wood charged therein and evolve from the wood a gas which is utilized in our plant for delivery at the nozzle to 90 perform useful service. The flow of gas from the hose-line 2 into the chamber of the nozzle creates therein a suction to draw in the proper volume of atmospheric air necessary to support combustion, and this is aided by 95 the supply of hydrocarbon fuel obtained from the pipe 22 and the jet 23. The operator is able to direct the delivery-nozzle so as to apply the heat and flame against the frozen soil, so as to thaw the latter sufficiently to enable 100 it to be mined by picks, bars, or other implements or machinery.

In our apparatus the retorts are placed in such a manner and so connected together that their action is reciprocal, thereby enabling a 105 continuous flame of uniform size and force to be maintained at all stages of the operation. The blast of flame is maintained at the nozzle for useful service by the pressure of the gas in the retort and superheater manifolds, and the volume of the flame is augmented by the addition of the atmospheric air and the hydrocarbon fuel. The gas is produced directly from wood or other gas-producing substance and is used in the performance of useful work without purification other than passing it through the manifolds of the superheater, by which the intensity of heat of the gas is very greatly augmented. The delivery-nozzle has its chamber of large capacity to enable the gas to expand therein after issuing from the line of hose, and with the superheated gas is combined the air and hydrocarbon fuel, thus bringing the gas or admixture to a condition in which it may be 115 ignited before final discharge from the orifice of the delivery-nozzle.

The apparatus may also be employed for the purpose of thawing out a ventilating-shaft, as represented in Fig. 4. This ventilating-shaft may be equipped with a partition or wall to divide the shaft into two parts, through one of which fresh air may be admitted to the shaft and the mine, while the

foul air may be discharged from the mine through the other part of the shaft. In case the ventilating-shaft should become frozen and closed against the ingress and egress of 5 air the delivery-nozzle may be directed against the ice or other debris for the purpose of thawing the same and enabling the shaft to be opened for ventilation purposes.

It is evident that changes in the form and 10 proportion of parts and in the details of construction of the plant herein described may be made by a skilled mechanic without departing from the spirit of the invention.

Having thus fully described our invention, 15 what we claim as new, and desire to secure by Letters Patent, is—

1. A gas-producer comprising a furnace, independent retorts supported therein, a series of superheater-manifolds arranged between 20 the retorts and the furnace-grate and having the manifolds thereof coupled in series for the continued circulation of gas, and valved connections between the independent retorts and the superheater-manifolds whereby the 25 gas from either of the retorts may be caused to traverse the entire area of the superheater-manifolds, substantially as described.

2. A gas-producer comprising a vertically-divided furnace, the independent retorts situated 30 in the respective compartments of said furnace and adapted for operation separately, the superheater having its manifolds arranged in the respective compartments of the divided furnace and coupled in series for the continued circulation of gas through all the manifolds, and valved connections between the independent retorts and the superheater whereby the gas from either retort may traverse 35 the entire series of manifolds of said superheater, substantially as described.

3. A gas-producer comprising a furnace, the independent retorts therein, the outlet-pipes connected with said retorts and having the vent-valves, a transverse pipe, 12, coupled to 45 the outlet-pipes within the vent-valves thereof and provided with the independent stop-cocks, a superheater, and a connecting-pipe attached to the branch pipe between the independent stop-cocks thereof and attached to 50 the superheater, substantially as described.

4. A gas-producer comprising a furnace, in-

dependent retorts supported in isolated compartments of said furnace and each opening through one end of the latter, a horizontal pipe connected with both retorts and provided 55 with vent-valves for the respective retorts, an off-bearing gas-pipe attached to said horizontal pipe, valves in said horizontal pipe on opposite sides of the point of attachment of the off-bearing pipe thereto, and a superheater 60 situated within the furnace below the retort and coupled with the off-bearing pipe, substantially as described.

5. A gas-producer comprising a vertically-divided furnace, independent retorts situated 65 in the respective compartments thereof, the superheater having its manifolds arranged within the furnace - compartments between the retorts and the grates and said manifolds connected in series by a return-elbow which 70 spans the division-wall of the furnace, valved connections between said retorts and one end of a superheater-manifold to direct the gas from either retort through the connected series of superheater-manifolds, substantially 75 as described.

6. A gas-producer comprising a furnace provided with a dividing-partition and forming isolated compartments therein, independent retorts within said isolated compartments of 80 the furnace and each having its end which protrudes from the furnace closed by a door, the superheating-manifolds supported within said compartments of the furnace below the retorts and exposed to the direct contact of 85 the flame and products of combustion therein, a return-bend connection between the isolated manifolds for connecting them in series, a horizontal pipe situated exteriorly to the furnace and connected with both retorts, 90 controlling-valves in said horizontal pipe, and an off-bearing pipe leading from said horizontal pipe to one of the manifolds, for the purposes described, substantially as set forth.

In testimony that we claim the foregoing as 95 our own we have hereto affixed our signatures in the presence of two witnesses.
